UNITED STATES PATENT OFFICE

ROBERT G. HANFORD, JR., OF COLUMBUS, OHIO.

DESIGN FOR A BUCKLE.

SPECIFICATION forming part of Design No. 13,832, dated April 3, 1883.

Application filed October 7, 1882. Term of patent 7 years.

To all whom it may concern:

Be it known that I, ROBERT G. HANFORD, Jr., of Columbus, in the county of Franklin and State of Ohio, have invented a certain new and original Design for Buckles, of which the following is a specification.

My design consists in a buckle having the side bars bent to form ogee curves between the bar to which the tongue is pivoted and the front bar on which the tongue bears, and also having the side bars bent outward between the bar to which the tongue is pivoted and the back bar.

The accompanying drawing is a perspective view of a buckle embodying my design.

a shows the side bars of the buckle. *b* is the front bar. *c* is the bar to which the tongue *d* is pivoted, and *e* is the back bar. The side bars, *a*, are bent in the form of ogee curves be-

tween the front bar, *b*, and the bar *c*, to which the tongue *d* is pivoted, and they are bent outward between the bar *c* and the back bar, *e*. The front bar, *b*, is bent or curved outwardly between the ends.

What I claim as my design, and desire to secure by Letters Patent, is—

A buckle having the side bars bent to form ogee curves between the bar to which the tongue is pivoted and the front bar, on which the tongue bears, and also having the side bars bent outward between the bar to which the tongue is pivoted and the back bar, substantially as specified.

ROBERT G. HANFORD, JR.
